(Cl. D45—4)

To all whom it may concern:

Be it known that I, Hans J. Duester, a citizen of the United States, residing at Route 1, Box 349-A, Norwood Park Station, Chicago 31, Illinois, have invented a new, original, and ornamental Design for an Extensible Band for Watch Bracelet or Analogous Article, of which the following is a specification, reference being had to the accompanying drawing forming a part thereof.

Figure 1 is a top view of an extensible band for watch bracelet or analogous article showing my new design;

Figure 2 is an end view thereof;

Figure 3 is an enlarged fragmentary top view thereof; and

Figure 4 is a sectional view taken along the line 4—4 of Figure 3.

I claim:

The ornamental design for an extensible band for watch bracelet or analogous article, as shown.
HANS J. DUESTER.
